ABSTRACT

Advancing means of a self-advancing mine roof support, or a part of the support which is moved thereby, is connected to or carries a section of rail adapted when advanced to register or line-up with a similar and separate section of rail connected to or carried by the advancing means, or a part moved thereby, of a neighbouring or adjacent support. The section of rail may be provided with means for temporarily connecting it to a neighbouring or adjacent section of rail. The sections of rail may serve as a means for connecting one support to a neighbouring or adjacent support so that one support will provide an effective abutment or anchorage for the advance of the other or a part thereof. The section of rail may include or be in the form of a spill plate or baffle. The spill plates or baffles, which are moved forwardly individually by the advancing means of their supports, then form a continuous barrier or wall in front of the supports and serve to prevent mineral spilling into the supports.

MINE ROOF SUPPORTS

This invention is for improvements in or relating to self-advancing mine roof supports. The invention is more particularly, but not exclusively, concerned with mine roof supports of the kind (hereinafter referred to as the kind specified) comprising at least two units which are advanced in turn by a pressure-fluid-operated device (e.g., a hydraulic ram), one unit serving when secured between floor and roof as an abutment or anchorage for said pressure-fluid-operated device when it is advancing the other unit.

Self-advancing roof supports are used extensively in mining where mineral is being extracted by the long-wall or shortwall method.

According to the present invention there is provided a self-advancing mine roof support in which the advancing means or a part of the support moved thereby is connected to or carries a section of rail adapted when advanced to register or line-up with a similar and separate section of rail connected to or carried by the advancing means, or a part moved thereby, of a neighboring or adjacent support. Said sections of rail may serve as a means for connecting one support to a neighboring or adjacent support so that one support will provide an effective abutment or anchorage for the advance of the other. Conveniently, the section of rail is provided with means for temporarily connecting it to a neighboring or adjacent section of rail.

According to a further feature of the invention there is provided a mine roof support of the kind specified wherein at least one of the units is provided with connecting means whereby it can be connected to a unit of a neighbouring or adjacent support or supports so that it will serve effectively as an abutment or anchorage for the advancing means of the support. Such a facility is of great advantage where roof and/or floor conditions are bad and said unit cannot be effectively secured between floor and roof so as to form a satisfactory abutment or anchorage for the advance of its associated unit of the support.

Conveniently, said section of rail or said connecting means includes, or is in the form of, a spill plate or baffle at the front of the support or the unit of the support which is advanced first in an advancing sequence.

One particular embodiment of the invention will now be described by way of example with reference to the accompanying drawings, in which:

FIG. 1 is a side elevation of a support with the units of the support in the position they occupy after a web of material has been cut from the mineral face,

FIG. 2 shows the support with its units in the position they occupy ready for a further web of material to be cut from the mineral face,

FIG. 3 is plan view of a pair of neighboring supports of the construction shown in FIGS. 1 and 2,

FIG. 4 is a diagrammatic plan view showing a series of the supports at the mineral face, the units of the supports being in the position they occupy during the passage of a mineral cutting machine in front of them along the mineral face,

FIG. 5 is an end view of FIG. 4,

FIG. 6 is a further diagrammatic plan view, the units of the supports on the left-hand side being in the position they occupy immediately after they have been passed by the mineral mining machine,

FIG. 7 is an end view of FIG. 6,

FIG. 8 is a further diagrammatic plan view showing the units of the roof supports in the position they occupy when the cutting machine is ready to fit from the tail gate back to the main gate, and

FIG. 9 is a plan view of a further embodiment of the invention.

Referring first to FIGS. 1, 2 and 3, the support comprises a rear unit 10 and a forward unit 11.

The rear unit 10 comprises a base 12 having mounted on it four hydraulically extensible telescopic props or legs 13 which support on their upper ends, in the usual way, a roof-engaging canopy 14. The base 12, of the rear unit, also has mounted on it, in side-by-side relationship, two hydraulically extensible telescopic props 15 and 16 which support respectively cantilever roof-engaging members 17 and 18. The cantilever members 17 and 18 are pivotally connected to the canopy 14 at 19 and 20 respectively.

The forward unit 11 of the support comprises a base 21 on which is mounted a single hydraulically extensible telescopic prop 22 having mounted on its upper part a roof-engaging member 23 which is substantially shorter than the roof-engaging members 17 and 18 in the direction of advance. The roof-engaging member 23 is movable longitudinally of and is guided between the roof-engaging members 17 and 18 of the rear unit. During such movement the roof-engaging member 23, of the forward unit, is also guided by wire rope guides 24 having their ends secured to the cantilever members 17 and 18 at 25 and 25a and passing through vertically elongated slots in brackets or lugs 26 and 27 (see FIG. 2) on the roof-engaging member 23. This prevents the roof-engaging member 23 rotating about the axis of the prop 22 and engaging under or over the bars 17 and 18 and, therefore, simultaneously preventing roof-engagement of all three roof-engaging members. Similarly, when the rear unit is being advanced it is guided by the rope guides 24 moving through the slots in the guide lugs 26 and 27.

The wire rope guides 24 serve the purpose described and at the same time permit any necessary movement of the units due to floor or roof irregularities.

Relative movement between the rearward and forward units 10 and 11, to advance the support as herein-after described, is effected by upper and lower double acting hydraulic rams 28 and 29. The ram 28 has its cylinder secured by trunnions 30 in the roof-engaging member 23 of the forward unit and its piston connected at 31 to the canopy 14 of the rear unit. The cylinder of the lower ram 29 is secured in the base 12 by trunnions (not shown) and its piston is connected to the base 21 of the forward unit 11 at 32.

For the purpose of the present invention a connecting means 33, which includes a spill plate or baffle 34 for preventing mineral spilling into the support is connected, by slot and pin means 34a, to the front of the base 21 of the forward unit. The slot and pin means 34a allow for some vertical movement or adjustment of the spill plate.

Referring now to FIGS. 4 to 8 of the drawings, FIG. 4 shows the condition in which the forward units 11 have been advanced relatively to the rear units 10 and the roof support system is ready for the machine M to remove a web of mineral from the face F.

As the machine passes the supports their rear units are advanced, by retracting the rams 28 and 29, so that the cantilever roof-engaging members 17 and 18 pro-

vide immediate support under the newly exposed roof as shown in FIG. 7. It will be appreciated that during this operation the front units of the supports, which are secured between floor and roof, serve as anchorages for the rams 28 and 29 so that they can advance the rear units which have temporarily been released from between floor and roof. If roof and/or floor conditions are bad there is a possibility of a forward unit being dislodged during this advance of its associated rear unit. To guard against this, such a forward unit may be connected, by its connecting device 33, to the corresponding connecting devices of the forward units of supports on either side of it as indicated at 33a. For example, the ends of the spill plate may have lugs provided with holes which register to receive bolts for connecting two spill plates together.

As the machine flits back from the tail gate the front units of the supports are advanced behind it, as shown in FIG. 9, by extending the rams 28 and 29 so that when the machine arrives back at the main gate the roof support system is in the condition shown in FIGS. 4 and 5 ready for the machine to cut a further web of material from the face.

It will be noted that the spill plates or baffles 34, which are moved forward individually by their supports, form a continuous barrier or wall or walls in front of the supports and will prevent mineral spilling into the supports.

The further embodiment of the invention shown in FIG. 9 is similar in some respects to that already described and where applicable like reference figures have been used to designate like parts. In this embodiment, however, the supports are single unit supports which operate in pairs and have been designated A1 and B1, A2 and B2 etc. Each support comprises a base 35 and four hydraulic props 36 mounted on said base and which support a roof-engaging structure or canopy on their upper parts in the usual way. The extensible members 37 of the advancing rams 38, of each pair of supports, are connected to a section of rail 39 which may carry or be in the form of a spill plate. Means are provided at 40 for temporarily connecting neighbouring sections of rail together.

The operating sequence may be as follows:

The rams of the pair of supports A1, B1 are extended so as to advance their section of rail from the position shown in full lines to the position shown in chain lines. That section of rail is then connected by the means 40 to the section of rail of a neighbouring previously advanced pair of supports, not shown, to the right of the pair of supports A1, B1. The props of the support B1 are then lowered and its ram is retracted so that it is advanced, following which it is re-set between floor and roof. The props of the support A1 are then lowered and its ram is retracted so that it also is advanced and then reset between floor and roof. The connecting means 40 will not be removed until it is again necessary to advance the section of rail.

The pairs of supports A2, B2 etc. are similarly advanced.

It will be understood that the connected rail sections, in combination with supports secured between floor and roof, provide an anchorage for the advance of the supports by their advancing rams.

I claim:

1. A self-advancing mine roof support system comprising a series of hydraulically extensible self-advancing roof supports each having hydraulic ram means, operative to advance it in turn in relation to other supports of the system, and a section of an upstanding retaining wall at its forward part, to keep mined mineral clear of the support system and confine it to an area being worked, connected to or carried by

10 the advancing means of the support or by a part of the support which is advanced thereby, and disconnectable connecting means connecting said upstanding retaining wall sections together so that each section can be disconnected from its neighbour for its advance and subsequently be connected to the retaining wall section of a neighbouring previously advanced support whereby said previously advanced support provides an anchorage or abutment for the advance of the next support, or part thereof, in the series.

2. A mine roof support system comprising a series of pairs of independently operable hydraulically extensible self-advancing roof supports, each pair having hydraulic ram means for advancing first one and then the other of the pair, each support of a pair serving in turn

20 when secured between floor and roof, as an abutment or anchorage for the advance of the other, an upstanding retaining wall positioned in front of the series of supports to keep mined mineral clear of the support system and confine it to an area being worked, said retaining wall being in separate sections, there being one

25 such section connected with the hydraulic ram means of each pair of supports so as to be advanced thereby, and disconnectable connecting means connecting said upstanding retaining wall sections together so that each

30 section can be disconnected for its advance and subsequently reconnected to a neighboring wall section and thereby to the neighbouring pair of supports having said neighboring wall sections, whereby an anchorage is provided, for the advance of at least one support of each pair, which comprises the other of the pair and also a neighbouring pair of supports.

3. A mine roof support system as claimed in claim 2 wherein each pair of roof supports comprises a rear support and a forward support connected together by

35 the hydraulic ram means, the upstanding retaining wall section being attached to the front of the first to be advanced support of the pair.

4. A mine roof support system as claimed in claim 3 wherein each pair of supports comprises two side-by-

40 side supports each having a hydraulic advancing ram, the two advancing rams being attached to the upstanding retaining wall section, of said pair of supports, and extended simultaneously for the advance thereof, ahead of the supports, and attached to the roof supports and retracted successively for the advance of the supports of the pair in turn.

5. A mine roof support system as claimed in claim 1 wherein the upstanding retaining wall sections are connected to the advancing means of the supports or to

45 parts of the supports which are advanced thereby, by a pin and vertically elongated slot arrangement which allows for some vertical movement of said retaining wall sections.
